(57) **CLAIM**

The ornamental design for a portable electronic device case as shown and described.

DESCRIPTION

FIG. 1 is a perspective view of a portable electronic device case embodying the invention.

FIG. 2 is a first side view of the portable electronic device case of FIG. 1.

FIG. 3 is a second side view of the portable electronic device case of FIG. 1.

FIG. 4 is a third side view of the portable electronic device case of FIG. 1.

FIG. 5 is a fourth side view of the portable electronic device case of FIG. 1.

FIG. 6 is a front view of the portable electronic device case of FIG. 1; and,

FIG. 7 is a rear view of the portable electronic device case of FIG. 1.

The broken lines depict portions of the portable electronic device case that form no part of the claim.

1 Claim, 7 Drawing Sheets
